EDMUND F. SIPHER, OF WILKINSBURG, PENNSYLVANIA, ASSIGNOR TO WESTINGHOUSE ELECTRIC AND MANUFACTURING COMPANY, A CORPORATION OF PENNSYLVANIA.

SHIELDING SYSTEM FOR VAPOR-CONVERTERS.

1,272,548.

Specification of Letters Patent. Patented July 16, 1918.

Application filed August 28, 1915. Serial No. 47,900.

To all whom it may concern:

Be it known that I, EDMUND F. SIPHER, a citizen of the United States, and a resident of Wilkinsburg, in the county of Allegheny and State of Pennsylvania, have invented a new and useful Improvement in Shielding Systems for Vapor-Converters, of which the following is a specification.

My invention relates to shielding systems for vapor converters, and it has for its object to provide a system of the character indicated that shall insure a uniform distribution of the power arc over all portions of the anode under widely varying amounts of load. My invention further relates to anodes particularly adapted to be employed with a shielding system of the character indicated.

In the accompanying drawing, Figure 1 is a side view partially in elevation and partially in section, of a vapor converter embodying one form of my invention; Fig. 2 is a side view, partially in section and partially in elevation, of an anode, together with its attendant shield, embodying a modification of my invention; and Fig. 3 is a detail sectional view illustrating a method of insulation that may be employed in the device of Figs. 1 and 2, if found desirable.

In the operation of vapor converters carrying relatively light loads, there is frequently a more or less uniform distribution of the arc over a large portion of the anode surface but, when the load is increased to large amounts, there arises a "stringing" phenomenon, the arc drawing together and concentrating upon a small spot on the anode. On the other hand, the converse phenomenon is frequently observed, the arc concentrating upon the more exposed portions of the anode at light load and spreading out over the anode surface to a greater and greater degree as the load increases. By my invention, I provide a shield for a large anode which tends to divide the arc thereto into a number of portions, each of said portions being directed to a different zone of the anode, thus insuring a more uniform distribution of the load upon the anode and preventing over-heating of limited portions thereof.

In connection with a shielding system embodying my invention, it is found desirable to employ anodes having elongated cylindrical shapes, and I find that an anode hav-

ing the desired characteristics may be manufactured from a piece of hot-rolled steel shafting, the interior of said shaft being bored out for the circulation of cooling fluid, if desired, the close and homogeneous structure of metal of the character indicated preventing leakage from the cooling space.

Referring to the accompanying drawing for a more detailed understanding of my invention, I show the container of a vapor converter of the metal-case type at 4 in Fig. 1. The container 4 is provided with a pair of anodes 5 and 6 and with a cathode 7, preferably composed of vaporizable reconstructing material, such, for example, as mercury or sodium. The anodes 5 and 6 and the cathode 7 are connected in a rectifier circuit of any usual form (not shown). The anodes 5 and 6 are preferably formed by boring out a piece of hot-rolled steel shafting and are provided with cooling tubes 13-13 for the circulation of fluid therethrough. The anodes 5 and 6 are further provided with shielding members, each of which comprises an insulated cylindrical conducting casing 8 which is open at its lower end. A deflecting cone 9 of heat-resistant material is supported below each of the members 8 and is spaced therefrom to permit the entrance of a rectifying arc. A plurality of conducting rings 10-10 are mounted coaxially with the anode 5 and are supported in any suitable manner, as by bolts 11-11 depending from the top of the member 8 and carrying suitable conducting spacing members 12-12.

Having thus described the structure of a converter embodying my invention, the operation is as follows: the power arc between the cathode 7 and one of the anodes, as, for example, 5, enters between the members 8 and 9 and passes up into the annular space between the member 8 and the rings 10. It is here divided into a plurality of portions by the action of the rings 10 and impinges upon corresponding zones of the anode 5, thus insuring uniform distribution of the arc over the anode under various conditions of load.

I find that, under certain operating conditions, at light load, the greater portion of the arc passes between the lower rings 10-10 to the lower portion of the anode but, upon a load increase, after a certain concentration of current at the active sur-

face is reached, portions of the arc flow through higher and higher spaces and impinge upon higher and higher portions of the anode, the amount of surface which is active varying roughly with the amount of load current. This is an exceptionally desirable method of converter operation.

Under certain conditions, I find it desirable to break the power arc before it reaches the rings 10, and I may therefore provide the anodes with shields constructed in accordance with Fig. 2 wherein a cylindrical member 8, surrounding the anode, supports a plurality of coaxial rings 14-14 at the lower portion thereof, a diaphragm 15 being disposed across the lower portion of the shield. A plurality of rings 10-10 are mounted between the anode and the member 8, as shown in Fig. 1.

20 A power arc, passing to an anode shielded as shown in Fig. 2 is first broken up into a number of streams which pass upwardly and are again separated by the rings 10 before impinging upon the anode.

25 In the modification shown in Figs. 1 and 2, I have shown the rings 10-10 and 14-14 as mounted upon conducting bolts carrying conducting spacers so that said rings are in conductive relation with each other. It may frequently be desirable, however, to insulate the conducting rings from each other so that heavy current flow through the rings, due to differences of potentials in different portions of the arc, may be obviated. 30 I may therefore construct the shield as shown in Fig. 3, wherein the conducting rings 16-16 are mounted upon a bolt 17, insulated by a refractory insulating tube 18, the rings 16 being spaced apart by refractory 35 insulating members 19-19. The members 18 and 19 may be composed of quartz, porcelain or similar material.

Throughout this description, I have explained the action of my device in accordance with the theory which seems most plausible in view of the present knowledge of the underlying phenomena. I desire it to be distinctly understood, however, that I do not confine myself to said theory of operation but merely present the same to aid in an understanding of the invention.

While I have shown my invention in its preferred form, it will be understood that it is susceptible of various minor changes 55 and modifications, and I desire, therefore, that only such limitations shall be imposed thereupon as are imposed by the prior art or are specifically set forth in the appended claims.

60 I claim as my invention:

1. In a vapor converter, the combination with an elongated electrode, of a shielding device therefor so shaped as to cause the arc to impinge thereupon in a plurality of 65 distinct zones.

2. In a vapor converter, the combination with an elongated electrode, of a shielding device therefor comprising a plurality of encircling members, whereby an arc to said electrode will be caused to impinge thereupon in a plurality of distinct zones. 70

3. In a vapor converter, the combination with a cathode, of an elongated anode radiating therefrom, and a shielding device associated with said anode and comprising a 75 plurality of members encircling the same so that an arc is forced to impinge upon said anode in a plurality of zones.

4. In a vapor converter, the combination with a cathode, of an elongated anode radiating therefrom, and a shielding device associated therewith and comprising a plurality of members encircling the same so that an arc is forced to impinge upon said anode in a plurality of zones, the zones nearest the 80 cathode alone being active during light loads and more and more distant zones becoming active as the load increases.

5. An electrode shield for a vapor converter including a plurality of coaxially 90 mounted rings of refractory material, said rings approaching so near to the anode surface as to substantially preclude the coalescence of the portion of the arc traversing one shield opening with that arc-portion 95 traversing an immediately adjacent opening.

6. An electrode shield for a vapor converter comprising a plurality of coaxially mounted rings of refractory material and a cylindrical member surrounding said rings 100 and spaced therefrom, said rings approaching so near to the anode surface as to substantially preclude the coalescence of the portion of the arc traversing one shield opening with that arc-portion traversing an 105 immediately adjacent opening.

7. In a vapor converter, the combination with an elongated anode, of a shield therefor comprising a plurality of refractory rings mounted coaxially therewith, and a baffle 110 member across the end of said electrode.

8. In a vapor converter, the combination with an elongated anode, of a shield therefor including a plurality of refractory rings mounted coaxially therewith, a baffle member across the end of said electrode, and a cylindrical member surrounding said rings and said baffle member and spaced therefrom. 115

9. In a vapor converter, the combination 120 with an elongated anode, of a shield therefor including a plurality of refractory rings mounted coaxially therewith, a baffle member across the end of said electrode, a cylindrical member surrounding said rings and said baffle member, and a baffle member across the end of said cylindrical member and spaced therefrom.

10. A casing member for an anode shield comprising a cylindrical member surround- 130

ing the anode proper, an arc-admitting member mounted on the end thereof and comprising a plurality of spaced coaxially mounted rings of refractory material, and 5 a baffle member across the other end of said arc-admitting member.

11. In a vapor converter, the combination with an elongated anode, of a shielding system therefor comprising a plurality of 10 spaced rings surrounding the anode, a baffle member across the end of the cylinder

determined by said rings, a cylindrical casting surrounding and spaced from said rings and baffle member, a plurality of spaced rings mounted on the end of said cylinder, 15 and a baffle member across the end of the cylinder determined by said last mentioned rings.

In testimony whereof, I have hereunto subscribed my name this 16th day of Aug. 20 1915.

EDMUND F. SIPHER.
